UNITED STATES PATENT OFFICE.

CLIFFORD L. CHRISTIAN, OF SAVANNAH, GEORGIA.

DIAPER-SUPPORT.

SPECIFICATION forming part of Letters Patent No. 786,728, dated April 4, 1905.

Application filed November 1, 1904. Serial No. 230,968.

To all whom it may concern:

Be it known that I, CLIFFORD L. CHRISTIAN, a citizen of the United States, residing at Savannah, in the county of Chatham and State of Georgia, have invented new and useful Improvements in Diaper-Supports, of which the following is a specification.

This invention relates to diaper-supports.

A disadvantage in diaper-supports as generally constructed is that they must be worn in addition to the usual underwear of the child, for which reason the free movement of the body is prevented and undue weight and warmth of clothes is caused. Furthermore, the element of expense is involved in the necessity of furnishing a child with a diaper-support in addition to the underwear.

The object of the present invention is to avoid the discomfort and expense attending the use of ordinary forms of diaper-supports.

With the foregoing and other minor objects in view, which will appear as the description proceeds, the invention resides in the combination, with an ordinary undershirt, of improved diaper-supporting means.

The invention also resides in the particular combination and arrangement of parts and in the precise details of construction herein-after described and claimed as a practical embodiment of the invention.

In the accompanying drawings, forming part of this specification, Figure 1 is a front elevation of a combined garment and diaper-support constructed in accordance with the invention. Fig. 2 is a similar view, the undergarment being unbuttoned in order more clearly to illustrate the diaper-supporting means. Fig. 3 is a detail view of an elastic tab suitable for use in connection with the invention.

Like reference-numerals indicate corresponding parts in the different views.

Referring to the drawings, the numeral 1 indicates an undergarment, which may be of any suitable size or weight. The undergarment 1, preferably, is open down the front and is provided with suitable buttons. Secured along one side of the opening at the front of the garment is a strong strip 2, which

is formed at its lower end with a plurality of 50 buttonholes 3. The stitching by which the strip 2 is secured in position terminates, preferably, above the upper buttonhole 3, so that the lower end of said strip will hang free. Adjustably and removably attached to the 55 lower end of the strip 2, by means of a button 4, is a diaper-supporting tab 5, the central portion 6 of which, preferably, is formed of elastic material. The diaper 7 (indicated conventionally in Fig. 1) is secured to the 60 lower end 8 of the tab by means of a safety-pin or other suitable device. Extending vertically down the back of the garment 1, from the neck portion thereof, is a strip 9, which is similar to the strip 2, said strip 9 being 65 formed at its lower end with a plurality of buttonholes, by means of which a diaper-supporting tab similar to that described may be adjustably and removably secured thereto.

It will be observed that both of the strips 70 2 and 9 extend only a portion of the way down the inside of the garment, so that said garment may be given any desired length. By adjustably and removably securing the diaper-supporting tabs to the strips 2 and 9, which, 75 as will be apparent, serve to strengthen the garment and to prevent it from being stretched out of shape by the diaper, said tabs may be adjusted to dispose the diaper in proper position. Furthermore, when the undergarment 80 is washed the tabs may be removed in order to prevent the loss of their elasticity through the action of water.

It will be apparent that the strip 2, in addition to its function of supporting the forward end of the diaper without imposing such strain on the garment as would destroy its shape, also serves the function of closing the seam down the front of the garment when it is buttoned, and thus protects the chest of the 90 child.

By combining the improved diaper-supporting means in the manner described with an ordinary form of undergarment the discomfort and expense of providing two separate articles 95 are avoided, as previously indicated.

In its particular combination and arrangement of parts and in its precise details of con-

struction the device of this invention constitutes an improvement over prior constructions intended for a similar purpose.

Minor changes in the precise embodiment 5 of invention illustrated and described may be made within the scope of the following claim without departing from the spirit of the invention or sacrificing any of its advantages.

Having thus described the invention, what 10 is claimed is—

The combination with a child's undergarment, which is open down the front, of a strip 15 of strong material extending a portion of the way down the center of the back on the inside thereof and terminating above the lower end

of the garment, a strip of strong material extending a portion of the way down one edge of the opening at the front and terminating above the lower end of the garment, the lower end of each strip being free and formed with 20 a plurality of buttonholes, and an elastic diaper-supporting tab buttoned to the lower end of each strip.

In testimony whereof I affix my signature in presence of two witnesses.

CLIFFORD L. CHRISTIAN.
